Inventor

C. B. Lyle.

UNITED STATES PATENT OFFICE.

CHARLES B. LYLE, OF MAGNOLIA, ARKANSAS.

INKSTAND-COVER.

No. 893,179.

Specification of Letters Patent. Patented July 14, 1908.

Application filed January 4, 1908. Serial No. 409,328.

To all whom it may concern:

Be it known that I, CHARLES B. LYLE, citizen of the United States, residing at Magnolia, in the county of Columbia and State of 5 Arkansas, have invented certain new and useful Improvements in Inkstand-Covers, of which the following is a specification.

This invention contemplates certain new and useful improvements in inkstands and 10 the object of the invention is an improved cover which is designed to render the inkstand air-tight and at the same time permit the ink to be instantly accessible to the pen, the inkstand being open but momentarily 15 when the pen is inserted. And a further object of the invention is a device of this character which excludes the dust and motes that are constantly falling into open inkstands and also prevents the evaporation of the ink.

20 With these and other objects in view that will more fully appear as the description proceeds the invention consists in certain constructions and arrangements of parts that I shall hereinafter fully describe and claim.

25 For a full understanding of the invention and the merits thereof, reference is to be had to the following description and the accompanying drawing, in which:

30 Figure 1 is a perspective view of my improved cover applied to an inkstand. Fig. 2 is a vertical longitudinal sectional view taken on the line $y-y$ of Fig. 3. Fig. 3 is a vertical sectional view taken on the line $x-x$ of Fig. 2.

35 Corresponding and like parts are referred to in the following description and indicated in all the views of the drawing by the same reference characters.

40 My improved ink stand cover comprises a body portion 1 which has a rounded front and a substantially flat back and which is formed at its bottom with an annular reduced portion 2, designed to fit into the mouth of the ink stand and form an air-tight joint therewith. This body portion 1 is formed 45 with a cylindrical valve chamber 3, the walls of which are inclined rearwardly, as shown, and the lower end of which extends through the bottom of the body portion and communicates with the mouth of the ink stand, to 50 constitute a valve seat 4 for a ball valve 5

mounted in such valve chamber. This ball valve 5 normally rests on its valve seat 4, and closes the same air-tight. The body portion 1 is formed in its front with a depression and a dip-hole 6 extending therefrom and leading inwardly and downwardly toward and into communication with the valve seat 4.

In order to permit the insertion of the ball valve into the valve chamber, the upper end 60 of said valve chamber extends through the back of the body portion, and is formed in its walls with threads arranged for engagement by a screw cap 8 to detachably secure the same to the body portion, the valve chamber 65 extending in the same direction throughout its length, so as to prevent the possibility of the ball valve becoming lodged in the valve chamber above its valve seat, and also to permit the valve chamber to be more conveniently and effectually cleaned.

70 In the practical use of my improved inkstand cover, a pen is inserted into the dip-hole and abuts against the side of the ball valve to force the latter from its valve seat 75 and up the inclined wall of the valve chamber, the pen being then thrust through said valve seat into the mouth of the inkstand. Upon the withdrawal of the pen, the ball valve will 80 obviously return at once to its normal position to close its valve seat and the mouth of the inkstand.

85 From the above description in connection with the accompanying drawing, it is evident that this is all accomplished without any additional trouble to the user, in short there is no cap to take off, no lid to put on, yet the stand is always closed but ready for immediate use.

Having thus described the invention, what I claim is:

An ink stand cover comprising a body portion formed with a rearwardly inclined cylindrical valve chamber, the lower end of which extends through the bottom of the body portion and constitutes a valve seat, said body portion being formed in its front with a depression and with a dip-hole leading downwardly and inwardly therefrom, into communication with the valve seat, a ball valve 95 100

mounted in the valve chamber and normally closing the valve seat, the upper end of the valve chamber extending through the back of the body portion, and being formed in its walls with threads, and a screw cap arranged for engagement with said threads, to close the upper end of the valve chamber, the walls of said valve chamber extending in the

same direction throughout their length, as and for the purpose specified. 10

In testimony whereof I affix my signature in presence of two witnesses.

CHARLES B. LYLE.
